[57] **CLAIM**

The ornamental design for an auxiliary circuit breaker system, as shown and described.

DESCRIPTION

FIG. 1 is a perspective view of an auxiliary circuit breaker system with the top cover raised showing my new design;

FIG. 2 is a side elevational view thereof, with the opposite side being a mirror image;

FIG. 3 is a front elevational view thereof;

FIG. 4 is a rear elevational view thereof;

FIG. 5 is a top plan view thereof; and,

FIG. 6 is a bottom plan view thereof.
